Primary Examiner — Cynthia Underwood(74) *Attorney, Agent, or Firm* — Millen, White, Zelano & Branigan, P.C.(57) **CLAIM**

The ornamental design for a tilt omelette bowl, as shown and described.

DESCRIPTION

FIG. 1 is a top perspective view of the tilt omelette bowl showing my new design.

FIG. 2 is a bottom perspective view thereof.

FIG. 3 is a side view thereof.

FIG. 4 is another side view thereof.

FIG. 5 is another side view thereof.

FIG. 6 is another side view thereof.

FIG. 7 is a top view thereof; and,

FIG. 8 is a bottom view thereof.

The broken lines in the drawings illustrate portions of the tilt omelette bowl which form no part of the claimed design.
